Primary Examiner — Paul D Bohannon(74) *Attorney, Agent, or Firm* — Weiss & Arons LLP(57) **CLAIM**

The ornamental design for a hybrid art table/easel, as shown and described.

DESCRIPTION

FIG. 1 is a elevational view of a hybrid art table/easel showing the design;

FIG. 2 is a back view thereof;

FIG. 3 is a front view thereof;

FIG. 4 is a side view thereof;

FIG. 5 is another side view thereof;

FIG. 6 is a top view thereof; and,

FIG. 7 is a bottom view thereof.

The broken lines showing of the hybrid art table/easel illustrate portions of the article that form no part of the claimed design.

1 Claim, 7 Drawing Sheets(56)
